WRENCH SET HOLDER

Charles H. Chur, Buffalo, N. Y., assignor to The Keystone Mfg. Co., Buffalo, N. Y., a corporation of New York

Application November 7, 1938, Serial No. 239,210

1 Claim. (Cl. 206—16)

This invention relates to a holder or container for compactly enclosing in a disassembled condition the various members of a wrench set so that when the same are not in use they may be stored easily and also carried about conveniently.

The object of this invention is to provide a holder or container for this purpose which is very simple in construction and low in cost and which not only permits of readily inserting the various members of the wrench set into the holder and removing the same therefrom but will also hold the various members of the wrench set securely and prevent the same from becoming displaced while being carried around as a unit.

15 In the accompanying drawing:

Fig. 1 is a side elevation of the holder embodying this invention and a wrench set packed therein.

Fig. 2 is a top plan view thereof.

20 Fig. 3 is a vertical longitudinal section taken on line 3—3, Fig. 2.

Figs. 4 and 5 are fragmentary horizontal sections taken on the correspondingly numbered lines in Fig. 1.

25 Fig. 6 is a fragmentary vertical transverse section taken on line 6—6, Fig. 1.

Figs. 7 and 8 are end elevations of the holder taken respectively toward the wide end and narrow end of the case and showing the retaining clasps moved out of engagement from the wrench set for permitting use of the same.

In the following description similar characters of reference indicating like parts in the several figures of the drawing:

30 The several members of the wrench set which are adapted to be stored in the holder or container of this invention may be differently constructed and also varied in number and form and the wrench set shown in the drawing may therefore be regarded as typical of one suitable for storage in the present holder. As there shown this wrench set comprises a plurality of sockets 10 each of which is provided at one end with an angular driving seat 11 of comparatively large diameter adapted to fit over and interlock with the head and nut of a bolt while its opposite end is provided with an angular coupling seat or of comparatively small diameter for receiving the means whereby the 35 socket is turned. The means shown in the drawing for turning the socket are of two kinds, one of which is adapted to turn the socket by means of an oscillating or ratchet action and the others by means of a continuously turning or positive action. The ratchet action operating

means comprise a coupling stud or pin 13 of angular form in cross section which is adapted to engage at one end with the coupling seat 12 in the small end of the socket and interlocked therewith, and a ratchet handle 14 provided at one end with a rotatable ratchet wheel 15 having a central angular seat 16 which is adapted to receive the other end of the coupling pin 13. Between this ratchet ring and the operating handle 14 is arranged a pawl mechanism 9 of 10 any suitable construction whereby turning of the ratchet handle 14 in one direction will compel the ratchet wheel to move with the same but permit the ratchet handle to move backwardly independently of this wheel. 15

The means for positively operating the socket in both directions preferably consist of a longitudinal operating handle 17 having a short coupling shank 18 projecting laterally from one end thereof, this handle bar and shank being 20 constructed in one piece and of hexagonal form in cross section so that when this shank is engaged with the angular coupling seat 12 of the socket these parts will be interlocked so that they are compelled to turn together. 25

The several sockets are of different sizes or diameters and when the several members of the wrench set are assembled these sockets are arranged in an upright position and in a longitudinal row with the largest socket at one end 30 and the smallest socket at the opposite end so that the row, as a whole, is generally of tapering form. In the assembled position of the several members of the wrench set the handle 14 of the ratchet operating mechanism is placed 35 lengthwise over the upper ends of the row of sockets and the coupling stud 13 is engaged at its end with the ratchet wheel 15 while its lower end is placed in the large driving end of the largest socket. At this time the bar 17 of 40 the positive operating handle is supported lengthwise on the upper side of the ratchet operating handle 14 and is held against lateral displacement thereon by engaging the underside of this bar with a retaining recess 19 on one 45 side of the front end of the ratchet handle 14, and the coupling shank 18 of the positive operating handle projects downwardly along the outer transverse side of the smallest socket. The rear end of the ratchet operating handle 14 is 50 preferably provided with the retaining seat 19 on both of its sides so that the longitudinal bar 17 of the positive operating handle may be nested with the ratchet handle and interlocked therewith when either of the sides of the ratchet 55

handle faces upwardly, it being understood that the coupling stud 13 may also be engaged with the ratchet wheel 15 from either side of the latter.

5 The several parts of the wrench set are shown in Figs. 1, 2 and 3 assembled in the manner just described.

The case of the holder is constructed of sheet metal and tapers in the direction of its length 10 so as to conform to the contour of the tapering row of sockets which are placed in this case with the largest socket at the wide end of this case and the smallest socket adjacent to the narrow end thereof. This casing comprises a flat bottom 20, two upright longitudinal side walls 21, 21 which converge from one end of the bottom to the other, a wide upright end wall 22 extending transversely across the wide end of the case and connecting the corresponding ends of 25 the bottom and side walls, and a comparatively narrow end wall 23 extending transversely across the narrow end of the case and connecting the corresponding ends of the bottom and side walls.

When the several members of the wrench set 25 are assembled in the holder, the largest socket is arranged close to or engages with the inner side of the wide end wall 22, and the smallest socket 13 is spaced from the narrow end wall 23, and the coupling shank 18 of the positive operating 30 handle projects downwardly into the space between the smallest socket and the narrow end wall 23, as best shown in Figs. 1 and 3.

While the positive operating handle is thus 35 assembled with the ratchet operating handle and the sockets, the shank 18 of the positive handle is interlocked with the case so as to hold the same against lateral movement therein. This is 40 preferably accomplished by means of a retaining or locking jaw 24 projecting upwardly from the narrow end wall 23 and formed integrally therewith and provided at its opposite lateral edges with retaining or locking lips 25 which receive 45 between them the depending coupling shank 18 of the positive handle, as best shown in Fig. 5. By this means the ratchet handle 14 is also held 50 at its rear end against lateral displacement inasmuch as the bar 17 of the positive handle engages with the upward facing notch 19 in this end of the ratchet handle, and the opposite or front end of the ratchet handle is held against lateral movement by reason of the coupling stud 13 engaging with both the ratchet wheel 15 and the driving seat 11 of the largest socket.

The row of sockets together with the ratchet handle resting thereon and the positive handle resting on the upper side of the ratchet handle are held against upward movement in the case 55 by retaining means which comprise two clasps mounted on opposite ends of the case and adapted to engage with the adjacent parts of the positive handle bar. Each of these clasps consists of a lower upright retaining arm 26 arranged on the outer side of one of the transverse end walls of the case and pivotally connected therewith by means which preferably consist of 60 a hollow rivet 27 extending lengthwise and horizontally through the lower parts of the arm 26 and the adjacent part of the respective end wall. At its upper end each of the retaining arms 26 is provided with a retaining finger 28 which projects longitudinally and horizontally inward from this arm and is provided on its underside with a concave locking face adapted to receive the adjacent upper convex part of the bar 17 of the positive handle. Each of the clasps is made of 65

sheet metal which is sufficiently resilient so that upon moving its finger 28 into its uppermost position the same will spring over the adjacent part of the handle bar 17 and interlock therewith, and upon swinging this clasp laterally to one side of the case, this finger will yield sufficiently to permit its seat to disengage from the handle bar 17. 5

Means are provided on the case for yieldingly holding the clasp at the wide end of the same in an upright operative position, which means 10 preferably consist of an upright retaining or locking jaw 29 formed integrally with this end wall and provided at its opposite lateral edges with retaining or locking lips 30 which receive between them the arm 26 of the respective clasp 15 when the latter is in its upright operative position, as best shown in Figs. 3 and 4. The outer sides of the lips 30 are rounded or bevelled so that the arm of this clasp upon being swung upwardly from either side of the case into a vertical operative position will engage the high part of the respective retaining lip by a wedge action and temporarily deflect the same sufficiently to permit this clasp arm to move into an upright position between the two retaining lips 30. In like 20 manner the arm of the clasp at the wide end of the case upon being moved laterally and downwardly from its upright operative position to its inoperative position will engage the high part of one or the other of the two retaining fingers 30 30 and thereby deflect the latter sufficiently to release this clasp.

It will be noted that the mouth of the retaining jaw 24 which receives the shank 18 of the positive operating handle faces inwardly while the mouth of the other retaining jaw 29 which receives the arm 26 faces outwardly, whereby the positive operating handle is held at both ends against lateral movement. In addition to holding the front end of the bar 17 of the positive operating 40 handle indirectly against lateral movement the clasp engaging therewith also holds the same against upward movement so that this particular clasp forms the double function of holding the bar of the positive handle against both lateral and vertical movement. The other clasp which is pivoted on the narrow end wall 23 of the case only engages with the bar 17 of the positively operating handle adjacent to the shank 18 thereof and this part of the positively operating handle is therefore held directly against lateral movement by the jaw 24. 45

By employing separate clasps at opposite ends of the case for holding the positively operating handle against displacement these clasps can be manipulated individually more easily than if they were constructed in one piece inasmuch as they are not liable to bind. 55

Moreover this construction of wrench set holder, as a whole, can be made of less metal than has been employed for this purpose heretofore and the several parts are so organized that they are not liable to get out of order when subjected to rough usage. 60

I claim as my invention:

A holder for a wrench set having a plurality 65 of sockets arranged in a row and a handle having an operating bar extending over said row of sockets and a shank projecting downwardly from the front end of said bar and along one end of said row of sockets, said holder comprising a trough shaped case which receives said row of sockets and the shank of said handle, two separate clasps having lower arms pivoted at their lower ends on the outer sides of the ends of said case so as to swing transversely thereto and 70

65

70

75

longitudinal fingers projecting inwardly from the upper ends of said arms and each having a concave face on its underside which engages over one end of said bar independently of the engagement of the finger of the other arm with the opposite end of said bar and two resilient retaining jaws formed on the transverse ends of said

case and one of said jaws having a pair of outwardly projecting locking lips which receive between them the arm of one of said clasps and the other retaining jaw having a pair of inwardly projecting locking lips which receive between them the shank of said handle. 5
